UNITED STATES PATENT OFFICE.

FREDRIC EDHOLM, OF ESKILSTUNA, SWEDEN.

FUEL-PUMP OF INTERNAL-COMBUSTION ENGINES.

1,222,270.

Specification of Letters Patent. Patented Apr. 10, 1917.

Application filed February 14, 1917. Serial No. 148,195.

To all whom it may concern:

Be it known that I, FREDRIC EDHOLM, a citizen of the Kingdom of Sweden, residing at Eskilstuna, Sweden, have invented new and useful Improvements in Fuel-Pumps of Internal-Combustion Engines, of which the following is a specification.

This invention relates to fuel pumps of internal combustion engines and more especially to the mechanism regulating the movements of such pumps, which are operated by means of a rotating cam disk or the like.

In most of the regulating mechanisms of said type the cam disk is actuated directly by a centrifugal governor which varies the length of the pump stroke. This construction is connected with the serious inconvenience that the pump pressure counters, to a great extent, the adjusting operation of the 20 governor fly-balls, which, on account thereof, are caused, during the rotation, to make violent oscillating movements, which will cause a rapid wear and tear of the governor. The said oscillating movements are rather 25 large, even during normal running of the engine, and will be highly increased, if the spraying nozzle be partially blocked up by deposits from the fuel.

The object of this invention is to obviate 30 to a great extent said inconveniences. To this purpose the cam disk or the like actuating the pump plunger is provided with a member movable in radial or approximately radial direction or rotatable concentrically 35 to the cam disk, the temporary position of said member being determined by the governor. Said member serves to control the movements of the pump plunger during the suction stroke of the pump and, consequently, to regulate the quantity of the fuel 40 drawn in. The disk itself is independent of the governor, which, consequently, cannot be influenced by the resistance acting on the pump plunger during the delivery stroke.

45 A preferred embodiment of the invention is illustrated in the accompanying drawing, in which:

Figure 1 is a longitudinal axial section through the casing of the regulating mechanism, certain parts of the mechanism being viewed from the side and other parts in section. Fig. 2 is a central cross-section through the casing showing certain parts in section on the broken line A—B in Fig. 1.

55 Referring to the drawing, 1 is the fuel pump casing and 2 is the pump plunger.

The outer end of the pump plunger is formed as a fork 20 serving as bearing for a roller 3. Inserted between the fork 20 and the pump casing 1 is a spring 11 tending to 60 move the plunger in the direction from the pump casing. 4 is a continuously rotating shaft driven in any manner from the crank shaft of the engine. Splined to the shaft 4 is a circular disk 5, which is provided with a flattening 21 and close to said flattening is a curved, flat member 6 journaled on a pin 7 fixed in the disk 5. The side 22 of the member 6 directed from the shaft 4 is formed as an arc having the same radius as 70 the disk 5, while the side 23 of the member 6 directed toward the shaft 4 is formed as an arc eccentric to the arc 22. The member 6 is so located that its side 22 extends beyond the flattening 21 and may, in its utmost position, cover the void space of the member 6 formed by the flattening 21, as is shown by dotted lines in Fig. 2.

The member 6 is, by means of a spring 8, kept in close contact with a wedge 9 connected with a ring 23', which is movable axially on the shaft 4 by means of a double-armed lever 24 connected with a centrifugal governor 10.

The mechanism described operates as follows, it being supposed that the shaft 4 rotates in the direction indicated by the arrow in Fig. 2. During the rotation of the shaft 4 the roller 3 is by the spring 11 kept in contact with the disk 5, until the roller at the point *a* comes in contact with the member 6, the position of which in relation to the pump plunger 2 depends upon the position of the wedge 9 in the longitudinal direction of the shaft 4, said latter position in turn depending upon the deflection of the centrifugal governor 10. The plunger 2 is, on account thereof, moved outward by the spring 11 a greater or smaller distance according to the position of the member 6, and during this movement the suction stroke is effected. When the roller 3 is in contact with the points *b* and *c*, as indicated by dotted lines in Fig. 2, and, consequently, touches the flattening 21, the delivery stroke commences and is continued, until the roller 3 reaches the point *d*. The roller 3 is, during the rest of the revolution, in contact with the circular portion of the disk 5, and, consequently, no movement of the plunger will take place.

While the roller 3 is in contact with the disk 5, that is to say during the delivery

stroke and while moving from *d* to *a*, the centrifugal governor is loaded only by the pressure caused by the spring 8, said pressure, however, being very small and, therefore, not being capable of preventing the fly-balls of the governor from being exactly adjusted between the suction strokes. During the suction stroke the governor is, in addition, acted upon by the pressure caused by the spring 11. This pressure is, however, constant and may be reduced to a comparatively small value and will therefore also exert a very insignificant influence on the movements of the governor.

Instead of the member 6 shown in the drawing a member rotatable concentrically to the disk 5 may be used, as for instance a member provided with a flattened portion and rotatable around the shaft 4, such member being adjusted in relation to the disk 5 by the centrifugal governor.

Having now particularly described and ascertained the nature of my said invention and in what manner the same is to be performed, I declare that what I claim is:

1. In an internal combustion engine, a fuel pump regulating mechanism, comprising a rotating member effecting the delivery strokes of the fuel pump, a member adjust-

ably attached to said rotating member and controlling the suction strokes of the fuel pump, and a governor controlling the position of the latter member in relation to the said rotating member.

2. In an internal combustion engine, a fuel pump regulating mechanism comprising a rotating cam disk having a flattened portion and effecting the delivery strokes of the pump, a member adjustably journaled to said cam disk and controlling the length of the suction strokes of the pump, and a centrifugal governor controlling the position of said member in relation to the flattened portion of the cam disk.

3. In an internal combustion engine, a fuel pump regulating mechanism, comprising a rotating cam disk effecting the delivery strokes of the pump, a curve-shaped member journaled to said cam disk and controlling the length of the suction strokes of the pump, a governor, and a wedge-formed member operated by the governor and adjusting said curve-shaped member in relation to the rotating cam disk.

In testimony whereof I have signed my name.

FREDERIC EDHOLM.
